US00D560133S

(12) **United States Design Patent** (10) Patent No.: **US D560,133 S**
(45) Date of Patent: **** Jan. 22, 2008**

(54) **SMOKE, FIRE, AND GAS DETECTOR**

(75) Inventor: **Carsten Heller**, Bad Salzdetfurth (DE)

(73) Assignee: **Wagner Alarm und Sicherungssysteme GmbH**, Langenhagen (DE)

(**) Term: **14 Years**

(21) Appl. No.: **29/259,289**

(22) Filed: **May 4, 2006**

(30) **Foreign Application Priority Data**

Nov. 4, 2005 (EM) 000426820

(51) LOC (8) Cl. **10-05**

(52) U.S. Cl. **D10/106**

(58) **Field of Classification Search** D10/104-121; D13/123, 110; D14/188; 439/650; 361/683; 340/628; 70/1.06, 431

See application file for complete search history.
